UNITED STATES PATENT OFFICE

163,331

SCARF

Quentin H. Sandler, Miami Beach, Fla.

Application January 11, 1951, Serial No. 13,748

Term of patent 14 years

(Cl. D3—12)

To all whom it may concern:

Be it known that I, Quentin H. Sandler, a citizen of the United States of America, and a resident of the city of Miami Beach, in the county of Dade and State of Florida, have invented a new, original, and ornamental Design for a Scarf, of which the following is a specification, reference being had to the accompanying drawing, forming a part thereof.

The figure is a plan view of a scarf, showing my new design.

I claim:

The ornamental design for a scarf, substantially as shown.

QUENTIN H. SANDLER.
